UNITED STATES PATENT OFFICE.

GEORGE J. FORAN, OF NEW YORK, N. Y., ASSIGNOR TO HENRY R. WORTHINGTON, A CORPORATION OF NEW JERSEY.

CONDENSING APPARATUS.

1,255,869.

Specification of Letters Patent.

Patented Feb. 12, 1918.

Application filed May 3, 1912. Serial No. 694,894.

To all whom it may concern:

Be it known that I, GEORGE J. FORAN, a citizen of the United States, residing at New York city, county of New York, and 5 State of New York, have invented certain new and useful Improvements in Condensing Apparatus, fully described and represented in the following specification and the accompanying drawings, forming a part of the 10 same.

This invention relates particularly to condensing apparatus of that class, in which the air is removed from the condenser and discharged by a hydraulic pump or compressor 15 of any suitable type, such for instance, as a liquid throwing pump or liquid injector, so that the air is compressed and carried away by the liquid. The air preferably in most cases is drawn off from the condenser 20 separately from the water of condensation, so that the hydraulic air compressor or pump handles only the air and uncondensed vapor, but in some cases the air and water of condensation may be handled by the hydraulic 25 compressor or pump. The especial object of the present invention is to provide an apparatus of this class, in which the water for the hydraulic air pump or compressor is circulated for re-use therein and 30 the air is efficiently separated from the water, so as to secure an efficient operation of the apparatus.

While the invention relates especially to combined condensing and air compressing 35 apparatus, as above stated, certain features of the invention, also, may be used generally in such liquid air compressing apparatus.

In the accompanying drawing, forming a part of this specification, there is shown for 40 the purpose of illustration, a condensing apparatus embodying all the features of the invention in their preferred form, and this apparatus will now be described in detail and the features forming the invention then 45 specifically pointed out in the claims.

In the drawing,

Figure 1 is a diagrammatic side elevation of the condensing apparatus, with the air compressing portion shown in vertical section, and showing a condensing apparatus 50 in which separate discharge pumps are used for the air and water of condensation.

Fig. 2 is a horizontal section on line 2 of Fig. 1.

55 Referring to the drawing, A is a surface

condenser having the hot well B from which the water of condensation is delivered through pipe 10, and centrifugal discharge pump C, and the air and uncondensed vapor are drawn off through pipe 11 by the hydraulic air discharge pump or compressor D. The hydraulic air discharge pump or compressor shown is the same as fully shown and described in United States Letters Patent to Otto Hildebert Mueller, No. 1,031,143, 60 dated July 2, 1912, having the rotating wheel *a* with axial passages receiving liquid through the annular port *b* supplied through pipe 12 from centrifugal circulating pump E, and delivering its liquid and compressed 65 air through nozzle 13.

In carrying out the present invention, the nozzle 13 delivers to tank F from which the circulating pump E takes its supply through pipe 14, and this tank is shown as having 70 the air outlet 15 at the top and pipe 16 for make up water. The air compressed in nozzle 13 may collect to such an extent as to interfere with the proper operation of the pump D or the circulating pump E so that 75 the full efficiency of the apparatus in maintaining the desired vacuum in the condenser A is not secured. To avoid this, means are provided for separating the air from the water at the bottom of the nozzle 13 so 80 that the air does not pass to the tank F, but is freed and escapes from the water as it is delivered from the nozzle. This result is secured by developing the bottom of the nozzle 13 into an annular passage 17 inclosing a 85 central air chamber 18, and forming in this annular passage one or more helical guides or vanes 1, two such guides being shown, by which the water is thrown outward spirally and separated from the air, and the latter 90 passes inward to the chamber 18, the bottom edge 2 of the chamber 18 being above the bottom edge 3 of the nozzle, to provide an air passage from the inner edges of the guides to the air chamber. The air then 95 passes from chamber 18 to the atmosphere through air escape pipe 19.

It will be understood that the invention is not limited to the special form of the means shown for separating the air from the 100 water, nor to the particular hydraulic air compressor shown, although these are the preferred forms for embodying my invention, but that the invention, broadly considered, may be embodied in apparatus widely 105 110

different in form. The condenser is shown as a surface condenser, but may be either a surface or jet condenser of any suitable type.

What I claim is:—

- 5 1. The combination with a steam condenser, of a hydraulic air discharge pump, a tank receiving the discharge water from the air discharge pump, a discharge passage from the air discharge pump extending below the level of the water in the tank and through which the air and water are discharged from the air discharge pump, a passage for the escape of air from the discharge water to the atmosphere, and means 10 for circulating water from the tank through the air discharge pump.
2. The combination with a steam condenser, of a hydraulic air discharge pump, a tank receiving the discharge water from the air discharge pump, an annular passage 15 extending below the level of the water in the tank and through which the air and water are discharged from the air discharge pump, an air passage within said annular passage having an air escape to the atmosphere, and means for circulating water from the tank through the air discharge pump.
3. The combination with a steam condenser of a hydraulic air discharge pump, a tank receiving the discharge water from the air discharge pump, an annular passage 20 extending below the level of the water in the tank and through which the air and water are discharged by the air discharge pump, an air passage within said annular passage having an air escape to the atmosphere, means for separating the air and water in said annular passage for discharge 25 through the air passage to the atmosphere, and means for circulating water from the tank through the air discharge pump.
4. The combination with a condenser, of

a hydraulic air discharge pump, a tank receiving the discharge water from the discharge pump, means for circulating water through the discharge pump and tank, an annular passage through which the air and water are discharged by the discharge pump into the tank below the level of water therein, an air chamber within said annular passage having an air escape to the atmosphere, and helical guides or vanes in said annular passage for throwing the water outward to separate the water from the air and permit the air to pass to the air chamber within the annular passage.

5. The combination with a hydraulic air compressor or pump, of a tank receiving the discharge water from the compressor, means for circulating water through the compressor and tank, an annular passage through which the air and water are discharged by the compressor into the tank below the level of water therein, an air chamber within said annular passage having an air escape to the atmosphere, and helical guides or vanes in said annular passage for throwing the water outward to separate the water from the air and permit the air to pass to the air chamber within the annular passage.

6. A hydraulic air compressor or pump having discharge nozzle 13 enlarged at its delivery end into annular chamber 17, in combination with discharge tank F, air chamber 18 within the annular passage 17 having an air outlet, and helical vanes 1 in passage 17.

In testimony whereof, I have hereunto set my hand in the presence of two subscribing witnesses.

GEORGE J. FORAN.
